R. V. KAIMER

LATCH FOR VEHICLE DOORS

Filed July 12, 1922

Inventor -
Richard V. Kaimer
by Segmowr & Eason
Atty.

UNITED STATES PATENT OFFICE.

RICHARD V. KAIMER, OF NEW HAVEN, CONNECTICUT, ASSIGNOR TO THE ENGLISH & MERSICK CO., OF NEW HAVEN, CONNECTICUT, A CORPORATION.

LATCH FOR VEHICLE DOORS.

Application filed July 12, 1922. Serial No. 574,446.

To all whom it may concern:

Be it known that I, RICHARD V. KAIMER, a citizen of the United States, residing at New Haven, in the county of New Haven and State of Connecticut, have invented a new and useful Improvement in Latches for Vehicle Doors; and I do hereby declare the following, when taken in connection with the accompanying drawings and the characters of reference marked thereon, to be a full, clear, and exact description of the same, and which said drawings constitute part of this application, and represent, in—

Fig. 1 an inside view, partly in section, of a latch for vehicle doors constructed in accordance with my invention.

Fig. 2 a sectional view, on the line 2—2, of Fig. 1.

Fig. 3 a face view of a modified form of my invention.

This invention relates to improvement in latches for vehicle doors, and particularly to latches which are adapted to be operated from the inside by a latch-bolt operating-lever, and from the outside by a rotatable handle. In the more general construction of latches for vehicle doors, the outside handle can only be turned in one direction, owing to the limited space within the latch casing. The object of this invention is to produce a latch for vehicle doors which may be operated from the outside by turning the handle in either direction and which will not interfere with the sliding action of the door window, and the invention consists in the construction as will be hereinafter described and particularly recited in the claims.

In carrying out my invention, I employ a latch casing 5, in which is mounted the usual latch-bolt 6 projecting outward through the front face 7 of the latch case. This bolt is provided with an upwardly-projecting operating-arm 8 adapted to be turned by the movement of a double cam 9. This cam is usually operated from the outside by a handle-spindle, but in this construction I provide the cam with teeth 10 meshing with teeth 11 on a hub 12, which is mounted forward of the cam and is adapted to be turned by a spindle 13 of a handle from the outside of the door, not shown but of usual construction. Preferably, the latch-bolt is adapted to be operated from the inside of a door by a lever which, in this case, is a vertically-

arranged lever 14, provided at its upper end with a handle 15, and, in order to lock the bolt against retraction, I provide a locking-dog 16, provided at its lower end with a notch 17 to engage with a lug 18 projecting upward from the upper end of the cam 9. This dog is adapted to be depressed by a push-button 19 mounted in the handle 15 and connected with a sleeve 20, which bears upon the upper end of the dog. The dog is provided at its rear end with a cam-face 21 to be engaged by a pin 22 in the spindle 14, so that, when the spindle is turned to retire the bolt, the dog will first be lifted out of engagement with the cam 9. The usual roll-back 23 of a pin tumbler lock may be provided to engage with the dog 16 to lock the dog in its closed position from the outside of the door, this being a common arrangement in locks of this type.

Instead of employing the dog 16 for locking the cam 9, the cam may be provided in its upper end with a notch 24, to be engaged by a pin 25 at the upper end of a slide 26, which is adapted to be locked in place by the roll-back 27 of the usual pin tumbler lock, which is operated from the outside of the door. This slide 26 has an upwardly-extending handle 28 by which the slide 26 may be moved into or out of engagement with the cam when it is not locked from the outside.

As in the construction first described, the cam 9 has the same teeth 10 engaging with teeth 11 on the hub 12, and the bolt is adapted to be operated by a rotary or other spindle 29. With this construction, the bolt may be operated from the outside of a door by turning the handle in either direction and does not interfere with the movement of a window in the door.

I claim:

1. A latch for vehicle doors, comprising a bolt having an operating arm, a cam mounted in the casing and adapted to move the arm when turned in either direction, the said cam formed with teeth, and a hub mounted in the case forward of the said cam and provided with teeth meshing with the teeth on said cam and adapted to be turned by a handle-spindle.

2. A latch for vehicle doors, comprising a bolt having an operating arm, a cam mounted in the casing and adapted to move the arm when turned in either direction, the said

cam formed with teeth, a hub mounted in the case forward of the said cam and provided with teeth meshing with the teeth on said cam and adapted to be turned by a handle-spindle, and means for locking the cam against movement by the handle-spindle.

In testimony whereof, I have signed this specification in the presence of two subscribing witnesses.

RICHARD V. KAIMER.

Witnesses:

FRANCES I. MARTIN,
RUTH E. BRADLEY.
